METAL CLAD SWITCH

Raymond P. Mattern, Minneapolis, Minn., assignor to Minneapolis-Honeywell Regulator Company, Minneapolis, Minn., a corporation of Delaware

Application May 31, 1940, Serial No. 337,962

11 Claims. (Cl. 200—152)

This invention relates to improvements in the field of fluid filled switches, particularly of the metal clad type.

One of the main objects of the present invention is to provide a metal clad switch which has a minimum number of parts, is simple and inexpensive to manufacture, and which is small, compact, and yet durable under reasonably heavy loads.

Another object is to provide a metal clad switch having a pair of opposed metal cups, a partition of insulating material to separate them, and an insulating cover to hold them in assembled relation.

A further object of the invention is to leave a portion of the ends of the metal cups exposed to cooperate with resilient mounting members which rotatably support said switch and form the electrical connections thereto.

A still further object is to provide the cups with outwardly extending flanges which may act to compress a rubber gasket to aid in sealing the switch when the insulating cover holds the cups in place.

Still another object is to vulcanize the rubber gasket directly to the cups in order to more positively seal the switch.

These and other objects will readily become apparent as the following specification is read in the light of the accompanying drawing, in which:

Figure 1 is a general view of the button or rotary type switch and the mounting means therefor, the switch itself being shown in section;

Figure 2 is an end elevation of the device shown in Figure 1;

Figure 3 is a section of the switch shown in Figure 1 taken along the line 3—3;

Figure 4 is a detail view of a modified form of insulating partition which may be substituted in the switch of Figure 1 if desired;

Figure 5 is a section taken along the line 5—5 of Figure 4, and

Figure 6 is a sectional view of the elongated or tubular switch.

Any electrically conductive fluid may be used in this switch but for the purpose of this description this fluid will be referred to as mercury, which is the most commonly used for this purpose.

The button or rotary type switch disclosed in Figure 1 is composed of a pair of opposed metal cups 10 and 11 which are adapted to seat on the annular shoulders 12 and 13 in the partition 14.

This partition is composed of material which is electrically insulating and also arc resistant. In this particular case, the material chosen is a high strength moulded ceramic. The metal cups 5 10 and 11 are provided with outwardly extending annular flanges 15 and 16, which with the periphery 17 of the partition 14 form an annular channel. A synthetic rubber gasket 18 is located in this channel and is normally slightly wider than the channel so that as the cups 10 and 11 are forced into engagement with the shoulders 12 and 13, the gasket 18 is compressed, thus sealing the enclosure formed by the metal cups from the external air. In order to improve this seal, 15 the gasket 18 may if desired be vulcanized to the cups.

The cups 10 and 11 are provided with shoulders 20 and 21 and insulating cover 22 made up of a thermo-setting material such as Bakelite, is 20 formed under pressure around the circumference of the switch and in engagement with the shoulders 20 and 21 on the metal cups 10 and 11. As the cover 22 is moulded around the switch, considerable pressure is applied and the two cups 25 10 and 11 are forced against the shoulders 12 and 13 in the partition 14, thereby compressing the gasket 18 and forming a good seal for the switch. When the Bakelite cover hardens, it holds the parts firmly in their assembled position.

30 When the switch is being made, a small opening is left in one of the metal cups so that the air may be evacuated from the enclosure and the switch filled with the proper amount of mercury and hydrogen gas. It will be seen that the partition 14 divides the enclosure into two chambers and separates the mercury into two separate pools 24 and 25. An opening 26 is placed near the periphery of the partition 14 and with the switch in the position shown in Figure 1, this 35 opening is above the level of the mercury and therefore the two metal cups 10 and 11 are electrically separated. When the switch is rotated, however, the hole 26 will move below the surface of the mercury and the two pools 24 and 25 will

40 flow together through the opening 26 and electrically connect the two cups 10 and 11. One form which this opening can take is shown at 26 in Figure 3, the level of the mercury being shown by the dotted line 27.

45 As shown in Figure 3, the lower edge 28 of the opening 26 is the edge which finally separates the two pools of mercury 24 and 25 as the switch is rotated in a clockwise direction. As shown in Figure 1, this edge extends straight through the partition and as a result the mercury break may 50

occur at either one or the other ends of the hole. As a result, under heavy electrical loads the arc may sometimes strike one or the other of the metal cups directly thereby eroding the cups and contaminating the mercury. Therefore it is desirable, particularly under heavy loads, to design a partition in which the break between the two pools of mercury will always occur midway of the partition. The partition 45 disclosed in Figures 4 and 5 was designed with this object in view. In this form of partition, the breaking edge of the opening 46 is in the form of a V with the point 47 of the V midway of the partition. In this case the break will always occur at the point of the V which is at a maximum distance from the two cups and therefore the probability of the arc impinging directly onto one of the metal cups is lessened. As shown in Figure 4, the gradual sloping sides 48 of the V extend in an arc around the partition, which arc lies on a circle concentric with respect to the axis of rotation of the switch.

The switch is supported by means of a pair of brackets 30 and 31 which are suitably connected to a supporting member 32. The bracket 30 is provided with a washer shaped end 33 which fits over a projection 34 on the exposed end of the cup 10. The member 30 is also provided with a pair of resilient fingers 35 and 36 which are biased into engagement with the face 37 of the cup 10. The bracket 31 is provided with duplicate parts 33, 35, and 36 which cooperate with the cup 11 in exactly the same manner. These two brackets act to rotatably support the switch, and the three members 33, 35, and 36 which frictionally engage the faces of the metal cups act to electrically connect them in a circuit which may in turn be connected to the brackets 30 and 31 through the binding posts 38 and 39.

In order to rotate this switch, an insulating arm 40 may be suitably cemented or otherwise attached to the periphery of the switch, as shown in Figures 2 and 3. This handle may also be molded on the cover and form an integral part of it if desired. This arm 40 may extend through an opening 41 in a wall plate 42 where the switch is used for operating a house lighting circuit. It will be seen in connection with Figure 3 that if the arm 40 is in its raised position, the opening 26 will be above the level of the mercury and therefore the circuit through the switch will be broken. When the arm 40 is moved downwardly as indicated in dotted lines in Figure 3, the opening 26 will be below the level of the mercury and the circuit through this switch will be closed.

Figure 6 discloses an elongated or tubular type metal mercury switch. As in the case of Figure 1, two metal cups 51 and 52 are seated on opposite annular shoulders 53 in the partition 54. The partition 54 may be made of the same material as the partition in Figure 1. These cups are also provided with outwardly extending flanges 55 which compress a rubber gasket 56 as the cups are forced against the shoulder 53. If desired, the gasket 56 may be vulcanized to the metal cups in order to improve the seal between the enclosure and the outside air. The metal cup 52 is provided with an outwardly extending stem 58 which acts as one electrode terminal for the switch. The cup 51 is provided with an outwardly extending hollow stem 59. A Bakelite cover 60 is moulded about the switch under pressure so as to hold the cups 51 and 52 firmly in engagement with the shoulder 53. After these parts have been assembled the switch may be

evacuated and filled with mercury and hydrogen gas through the hollow stem 59 which may then be sealed off. This stem acts as the other electrode terminal for the switch.

5 The partition 54 is provided with a tapered hole 62 which extends through the center to provide a path through which the mercury within the switch may extend to electrically connect the two metal cups 51 and 52. Inasmuch as this hole 62 is concentric with respect to the axis of the switch, the rotative position of the switch is immaterial. The circuit is controlled entirely by tipping the switch one way or another. As the switch is tipped to a position where the stem 58 10 is higher than the stem 59, the mercury will flow toward the opening 62 and close the circuit through the switch. When the switch is tipped in the opposite direction, the partition 54 will 15 separate the mercury into two pools and break the circuit through the switch.

These specific forms described above are for 20 illustrative purposes only and therefore I wish to be understood that I am to be limited only by the scope of the appended claims and not by the specific forms.

25 I claim as my invention:

1. A switch comprising in combination, a pair of oppositely positioned dished metal cups, a partition of insulating material interposed between said cups separating them electrically, said cups seating on said partition, a quantity of electrically conductive fluid partially filling said cups, said fluid being separated into two pools by said partition, an opening in said partition whereby said two pools of fluid are connected through said opening for certain positions of said switch, a resilient gasket between said cups, and an insulating cover for said switch, said cover acting to hold said cups in a position to compress said gasket thereby aiding in sealing said switch.

2. A switch comprising in combination, a pair of oppositely positioned dished metal cups, a partition of insulating material interposed between said cups separating them electrically, said cups seating on said partition, a quantity of electrically conductive fluid partially filling said cups, said fluid being separated into two pools by said partition, an opening in said partition whereby said two pools of fluid are connected through said opening for certain positions of said switch, a resilient gasket between said cups, and a cover of thermo setting material moulded about said switch forcing said cups inwardly to compress said gasket and seal said switch.

55 3. A switch comprising in combination, a partition of insulating material, said partition having oppositely disposed shoulders, a pair of dished metal cups adapted to seat on said shoulders, flanges on said cups extending outwardly beyond the periphery of said partition, a resilient gasket around said partition between said flanges, a quantity of electrically conductive fluid partially filling said cups and separated into two pools by said partition, an opening in said partition whereby said two pools are connected through said opening for certain positions of said switch, and an insulating cover for said switch, said cover acting to hold said cups against said shoulders to compress said gasket and seal said switch.

4. A switch comprising in combination, a partition of insulating material, said partition having oppositely disposed shoulders, a pair of dished metal cups adapted to seat on said shoulders, flanges on said cups extending outwardly beyond the periphery of said partition, a resilient gas-

ket around said partition between said flanges, a quantity of electrically conductive fluid partially filling said cups and separated into two pools by said partition, an opening in said partition whereby said two pools are connected through said opening for certain positions of said switch, and a cover of thermosetting material moulded about said switch, said cover holding said cups against said shoulders and compressing said gasket to seal said switch.

5. A switch comprising in combination, a pair of oppositely positioned dished metal cups, a partition of insulating material interposed between said cups separating them electrically, said cups seating on said partition, a quantity of electrically conductive fluid partially filling said cups, said fluid being separated into two pools by said partition, an opening in said partition whereby said two pools of fluid are connected through said opening for certain positions of said switch, a rubber gasket located between and vulcanized to said cups, and an insulating cover for said switch, said cover acting to hold said cups in a position to compress said gasket.

6. A rotary type switch comprising in combination, a switch enclosure, a partition of electrically insulating material dividing said enclosure into two parts, a quantity of electrically conductive fluid in each part, and a relatively small opening near the periphery of said partition whereby connection between the two parts of said fluid will be alternately made and broken through said opening as said switch is rotated back and forth, that part of said partition which forms the breaking edge of said opening being in the form of a V with the point of the V substantially midway of the partition whereby the break will occur well within said opening, the sloping sides of said V lying on a circle concentric with respect to the axis of rotation of said switch.

7. A switch comprising in combination, a pair of oppositely positioned dished metal cups, a partition of insulating material interposed between said cups separating them electrically, a quantity of electrically conductive fluid partially filling said cups, said fluid being separated into two pools by said partition, an opening in said partition whereby said two pools of fluid are connected through said opening for certain positions of said switch, and an insulating cover circumferentially around said switch and extending partially over the ends to hold said cups and partition in assembled relation and at the same time leave a substantial portion of the ends of said cups exposed.

8. A switch comprising in combination, a pair of oppositely positioned dished metal cups, a partition of insulating material interposed between said cups separating them electrically, a quantity of electrically conductive fluid partially filling said cups, said fluid being separated into two pools by said partition, an opening in said partition whereby said two pools of fluid are connected through said opening for certain posi-

tions of said switch, an annular shoulder in the end of each of said cups, an insulating cover extending circumferentially around said switch and fitting into said shoulders to hold said cups and partition in assembled relation, said cover leaving a substantial part of the ends of said cups exposed, and a pair of resilient supporting members, the exposed ends of said cups including means for frictional cooperation with said supporting members for rotatably supporting said switch.

9. A switch comprising in combination, a pair of oppositely positioned dished metal cups, a partition of insulating material interposed between said cups separating them electrically, a quantity of electrically conductive fluid partially filling said cups, said fluid being separated into two pools by said partition, an opening in said partition whereby said two pools of fluid are connected through said opening for certain positions of said switch, an outwardly extending stem integrally connected to each cup, and an insulating cover moulded to said switch and stems and holding said cups and partition in assembled relation, said stems extending through said cover and constituting electrode terminals for said switch.

10. A switch comprising in combination, a pair of oppositely positioned dished metal cups, a partition of insulating material interposed between said cups separating them electrically, a quantity of electrically conductive fluid partially filling said cups, said fluid being separated into two pools by said partition, an opening in said partition whereby said two pools of fluid are connected through said opening for certain positions of said switch, an outwardly extending stem integrally connected to each cup, and an insulating cover, moulded to said switch and stems and holding said cups and partition in assembled relation, said stems extending through said cover and constituting electrode terminals for said switch, one of said stems being hollow so that said switch may be evacuated and filled through said stem.

11. A switch comprising in combination, a disc shaped partition of insulating material having oppositely disposed circumferential shoulders, a pair of oppositely disposed cup shaped terminals having portions seating in said shoulders and circumferential flanges extending outwardly in substantially parallel planes, a quantity of electrically conductive fluid partially filling said cup shaped terminals, said fluid being separated into two pools by said partition, said partition being provided with an opening through which said two pools are connected for certain positions of said switch, and an insulating cover of thermosetting material moulded by pressure about the circumference of said switch whereby it engages the flanges on said cup shaped terminals and holds them in firm engagement with said partition.

RAYMOND P. MATTERN.
